UNITED STATES PATENT OFFICE.

CHARLES R. PEDDLE, OF SUFFERN, NEW YORK, AND JAMES M. WALDRON, OF HIGHWOOD, NEW JERSEY.

SWITCH-OPERATING MECHANISM.

1,375,537.

Specification of Letters Patent. Patented Apr. 19, 1921.

Application filed October 4, 1919. Serial No. 323,473.

To all whom it may concern:

Be it known that we, CHARLES R. PEDDLE and JAMES M. WALDRON, citizens of the United States, residing at Suffern, in the 5 county of Rockland and State of New York, and at Highwood, in the county of Bergen, State of New Jersey, respectively, have invented certain new and useful Improvements in Switch-Operating Mechanism, of 10 which the following is a specification.

This invention relates to switch operating mechanisms for railroads and has for an object to provide a switch operating mechanism embodying new and improved features 15 of safety. In some switch operating mechanisms in use at the present time, provision is made to prevent the throwing of the operating lever when a car is in the switch block. This is accomplished by a lock, locking the 20 switch lever, which lock has its electro-magnetic releasing means cut out by short circuiting a battery in the switch block. It has occurred, on a number of occasions, that accidents have arisen from the fact that the 25 switch operating lever has been started toward a switch throwing position before the train has entered the switch block and after the lever has been started there has been no provision for preventing the complete 30 throw of the lever and therefore throwing the switch under the train. The object of the present invention is to prevent throwing a switch under a train when the train is in the switch block.

35 The drawing in the present case is purely diagrammatic and no feature of the same is to be considered as disclosing the mechanism actually employed which may be varied within a very wide range to meet the requirements of specific installations.

40 As disclosed in the drawing the operating mechanism is controlled from a battery B in circuit with a relay R, magnets M and M' and an operating lever L. The battery B is also at times in a circuit controlled by the 45 track relay R' in circuit with the track battery B'. As shown the track battery B' is connected with the side track ST but is also in circuit with the main track T in which is 50 located the switch S.

55 The rail 10 of the track T is provided with insulating joints 11, 11' and 12, 12', while the side track ST is provided with insulating joints 13, 13', 14 and 15. The rail 16 of the side track is connected with the rail 10 by

the bond 17. Current from the battery B' to the relay R' is therefore through the rail 16, bond 17, rail 10, relay R' rail 18 and rail 19. It is obvious that this relay R' may be deenergized by short circuiting by a car in 60 any position within the switch block as indicated by the several positions c, c' and c''. When the relay R' is energized from the battery B' the armature 20 is closed against the contact 21. When so closed current from 65 the battery B passes through the line B, 22, armature 20 and contact 21 and the line to R, through the line R, 23 and line 23, B to battery energizing the relay R and closing the armature 24 against its contacts 25 and 70 26 and the armature 27 against its contacts 28 and 29.

With the relay R closed the current is taken from battery B through the line B, 22, 30, 31, contact 25, armature 24, contact 75 26 to the switch 32 on the lever L. With the lever L in normal position as shown in full lines in the drawing, current passes from the switch 32 when closed through the line 33, 34 to the contact spring 35 through 80 the lever L to the contact spring 36 and through the line 37, M to the magnet M which is energized by completing the circuit through the line M, 38, 23 to battery B. The energizing of the magnet M at 85 attracts the armature 39 which has engaged against the lug 40 on the bar 41 to prevent the throwing of the lever L. The unlocking of the bar 41 permits the throwing of the lever L from the position across contact 90 springs 35 and 36 whereby the circuit to the magnet M is broken and the magnet deenergized. The bar 41, however, has moved so that the dropping of the armature 39 no longer locks the bar and the bar and lever 95 L are therefore free to move. In its normal position, however, and before moving, the lever L has closed contact between contact springs 42 and 43. These springs are in circuit with battery B through the line B, 100 22, 30, 31, 44, 45, 46, contact springs 43 and 42, line 47, 48 to solenoid 49 which acting upon the core 50 tends to hold the switch S closed clearing the main track T. Returning from the solenoid 49 current passes 105 through line 51, 52, 53, 23, to battery B. With the lever therefore in normal or full line position the current of battery B is on the solenoid 49 tending to hold the switch in such closed position. Current is also on the 110

solenoid 49 from battery B through the line 10 B, 22, 30, 31, 44, contact 28, armature 27, contact 29, 54, 55, 56 to contact spring 57, contact spring 58, line 59, 48, solenoid 49, line 51, 52, 53, 23 to battery B. It will be noted that the contact springs 57 and 58 cover a larger arc than the contacts 42 and 43. The movement of the lever to the position *a* breaks contact with the springs 35, 36, 15 and 42, 43 but contact between the springs 57 and 58 is still maintained whereby although the current to the solenoid 49 through the contact springs 42 and 43 has been interrupted, the current, through the 20 springs 57 and 58 is still maintained. The throwing of the lever therefore to the position *a* to break the current through the springs 42 and 43 does not deenergize the solenoid 49. When however the lever L has 25 passed off from the springs 57 and 58 it has made contact with the springs 60 and 61. The circuit including the springs 60 and 61 is from the battery B through armature 27 of relay R to 54, 62, to springs 61 through the lever L to spring 60 through the line 60, 63 to solenoid 64 the core of which, 65, locks 30 the bar 50 which is employed as a core of the solenoid 49 and when moved to throw the switch S. The locking core 65 is normally held in locking engagement by a 35 spring 66 but when the solenoid 64 is energized its locking core 65 is withdrawn from engagement with the bar 50. The circuit for solenoid 64 is completed through the line 51, 52, 53, 23 to battery B. Unless however 40 the relay R is closed current does not pass through the springs 60 and 61 to energize the solenoid 64 and if a car is in the switch block the relay R' being deenergized, opens 45 the circuit to the relay R whereby such relay R being deenergized current does not pass through the springs 60 and 61 to the solenoid 64 and the switch remains locked notwithstanding the movement of the lever L from 50 normal to any other position. The lever may be thrown wholly to make contact with the springs 43' and 42' which will energize the solenoid 67 tending to throw the switch S, but in view of the fact that the switch 55 remains locked, the switch cannot be thrown. Therefore with a car in the switch block, although the relation of the parts initially may have been such as to unlock the lever L by the energizing of the magnet M, the lever 60 may be thrown through its complete arc without throwing the switch under the train. The springs 57' and 58' are in such position relative to the springs 57 and 58 that the interval between the two sets of springs is 65 practically no more than the width of the lever L so that when contact between the springs 57 and 58 is broken, it is almost instantaneously made between the springs 57' and 58'. If the relay R is closed current is taken through the springs 57' and 58'

to the solenoid 67 passing from battery B, 30, 31, 44 through armature 27, line 54, 62, 68, 69, 70, 71 to solenoid 67 returning to battery through the line 72, 52, 53, 23 to battery B. Such energizing of the solenoid 67 through the springs 57' and 58' can only occur if the relay R is closed.

When the lever L has reached the position *d* the lock is held in unlocked position by the energizing of the solenoid 64 being energized through the springs 60 and 61 and the solenoid 67 is energized through the springs 57' and 58' and the switch S is thrown to open the track to the side track ST. An appreciable time, however, is required for the throwing of the switch S and to provide that the lever L shall not complete its movement before the switch S has reached its limit of movement, the parts are so arranged that when the lever L has reached the position *d* with the solenoids 64 and 67 both energized the armature 73 is in engagement with the lug 74 of the bar 41 preventing a further movement of the lever L until the armature 73 has been released from the lug 74. Provision is therefore made for holding the parts with the lever at position *d* until the switch S has completed its movement. This provision comprises a switch 75 actuated by the bar 50, 95 With the switch 75 in the position shown in the drawings, it is out of circuit. When, however, the switch completes its movement the switch 75 is brought into engagement with contact 76. Current is now taken 100 from battery B through line 22, 30, 31, 44, contact 28, armature 27, contact 29, line 54, 62, spring 61, spring 60, line 77, 63 to switch 75, contact 76, line 78, contact 79, switch 80, contact 81, line 82, 83, 84 to magnet M', 38, 105 53, 23, to battery B. The energizing of the magnet M' lifts the armature 73 to release the lug 74 permitting the completion of the movement of the bar 41 and the lever L. The completion of the movement of the bar 110 41 throws the switch 80 out of engagement with the contacts 79 and 81 against the tension of over-center spring 85 breaking the circuit through the switch 75 thereby deenergizing magnet M' and allowing armature 73 to drop behind lug 74. This completion of the movement of the lever L to the position *f* makes contact with the springs 35', 36', 42' and 43' and is the limit of its movement. The passing of the lever from 120 the position *d* to *f* and off the springs 60, 61 deenergizes the solenoid 64 permitting the spring 66 to throw the locking core 65 into locking position.

For the return movement of the switch 125 the reverse is true in all respects. The closing of the switch 32 when the lever is in the position *f* energizes the magnet M' which attracts the armature 73 which has now locked behind the lug 74 permitting bar 41 130

to move in the opposite direction. When the lever has moved to the position so that contact is established between the springs 57 and 58 and the springs 60 and 61 the sole-
 5 noids 64 and 49 are energized throwing the switch S back to full line position. At that position the armature 39 locks upon the lug 40 upon the side opposite that shown in full lines compelling the stoppage of the lever
 10 L until the switch S has completed its move-
 ment closing the switch 75 against its contact 76' and the switch 80 now being against the contacts 79' and 81' energizes the mag-
 15 net M lifting the armature 39 and permit-
 ting the completion of the movement of the lever L to full line position.

It is obvious that the movement of the switch S will be almost instantaneous and can only occur if the track relay R' is ener-
 20 gized from the battery B' indicating a clear switch block.

At times and under certain conditions the apparatus of the track relay R' or the relay R may get out of operative condition
 25 which would delay the operation of the trains. To provide for this contingency, a manual key 86 is provided adapted to en-
 gage contact 87 whereby current is taken from battery B through the line to 30, key
 30 86, contact 87, line 55 to 54, thus cutting out the relay R. It is proposed that the key 86 be located in a locked box the key of which is in the possession only of one who is authorized to operate the device other
 35 than in the usual and ordinary manner.

Having thus fully described our said in-
 vention, what we claim as new and desire to secure by Letters Patent, is:

1. The combination with a railway switch,
 40 of electrical means for controlling the oper-
 ation of the switch, a manually-movable part, a source of electrical energy, means controlled by the movable part in circuit with the source for maintaining the switch-
 45 moving mechanism inoperative, means con-
 trolled by the moving part at a certain pos-
 ition of its movement controlling mecha-
 nism for releasing the switch, means con-
 trolled by a further movement of the moving
 50 part for throwing the switch to its opposite
 limit, and means controlled by a train in
 block with the switch for throwing the mov-
 ing part out of electrical control at any
 point in its movement.

55 2. The combination with a railway switch,
 of mechanism for moving the switch be-
 tween its limits of movement, a manually-
 movable part in circuit with a source of elec-
 trical energy adapted to control the switch-
 60 operating mechanism, a circuit controlled by
 the moving part in its initial position for
 maintaining the switch at its then limit of
 movement, a circuit controlled by the mov-
 ing part in an advanced position for releas-
 65 ing the switch and permitting the mecha-

nism to throw the switch to its opposite limit, means for maintaining the switch in its thrown position, and means controlled from a train in the switch block to interrupt the operative effect of the moving part at 70 any position in its movement.

3. The combination with a railway switch located in an insulated block, of a source of electrical energy connected with the units of the block, a relay electrically connected 75 through the block units with the source of electrical energy in such manner that a train in any position in the block will short circuit the source of energy and deenergize the relay, switch-operating mechanism, a 80 manually movable part in circuit with a second source of electrical energy, means in part carried by the movable part for transmitting energy from the second source to the switch-operating mechanism to main- 85 tain the switch at its initial limit while the moving part remains in initial position, means carried by the moving part for trans-
 90 mitting energy from the second source to the switch-operating mechanism in an ad-
 vanced position of the moving part to re-
 lease the switch retaining mechanism and put into operation the switch-throwing mechanism, means to restrain the movement of the moving part until the switch has 95 completed its movement, means energized from the completion of movement of the switch to release the moving part, means actuated by a completion of movement of the moving part to interrupt the last men- 100 tioned energizing effect, and means to in-
 terrupt energy from the second mentioned source through the moving part at the open-
 105 ing of the relay connected with the first mentioned source.

4. The combination with a railway switch located in an insulated block, of a source of electrical energy connected with the units of the block, a relay in circuit with the source through the units of the block and 110 adapted to be deenergized by short circuiting the source by a train at any point within the block, switch-operating mechanism, switch-locking mechanism, a series of cir-
 115 cuits including a source of circuit energy, a moving part, means carried by the mov-
 ing part in its initial position for transmit-
 ting energy from the circuit source to the switch-operating mechanism to maintain the switch in its initial position, circuits closed 120 by the moving part at an advanced posi-
 tion to release the locking mechanism and energize the switch-controlling mechanism to throw the switch to its opposite limit, a circuit controlled by an electric switch in 125 turn controlled by the movement of the railway switch for interposing an obstruc-
 tion to the movement of the moving part at the point of unlocking the railway-switch mechanism and energizing the switch-con- 130

- trolling mechanism to permit time for a complete movement of the railway switch, means energized by said last mentioned circuit for releasing the obstruction when the 5 railway switch has completed its movement, and means controlled by the block-relay for opening the circuits to the moving part at any point between its initial and final positions.
- 10 5. The combination with a railway switch located in an insulated block, of a source of electrical energy connected with the units of the block, a block-relay electrically connected with the source of energy through 15 the block-units and adapted to be deenergized by the short circuiting of the source by a train positioned at any point within the block, a source of energy connected with a plurality of circuits some of which 20 are opened and closed by the block-relay, a moving part, a circuit including the moving part at either extreme of its movement excluding the block-relay control for controlling the switch-operating mechanism to 25 hold the switch at either extreme of its movement, a circuit including the moving part having interrupting mechanism controlled by the block-relay adapted when energized to release the switch, a circuit including the moving part adapted to be interrupted by the action of the block-relay for energizing the mechanism for throwing the switch to the opposite limit of its movement, means for locking the switch at a 30 further movement of the moving part when current to the locking mechanism has been interrupted and a circuit exclusive of the block-relay control and closed at the extreme movement of the moving part for 35 maintaining the switch at such position.
6. The combination with a railway switch located in an insulated block, a source of electrical energy connected with the units of the block, a relay electrically connected 40 with the units of the block and energized from the block-source of energy and adapted 45 to be deenergized by short circuiting the source by a train at any point within the block, switch-throwing mechanism, a plurality of circuits including a source of circuit energy, a moving part adapted at its initial position to close one of the circuits from the circuit source to the switch-throwing mechanism to hold the switch in its initial position, means carried by the moving part to close a circuit from the source of circuit energy to the locking mechanism to release the lock at an advanced position of the moving part, a circuit controlling the switch-throwing mechanism adapted to 50 energize the switch-throwing mechanism through the moving part and the circuit source at a further advanced position of the moving part, means controlled by the block-relay for interrupting the circuits through the moving part at either of its advanced positions to prevent the releasing of the switch-locking mechanism, and means at the switch-throwing position of the moving part to obstruct the further movement of the moving part until the throwing of the switch has been completed, means controlled by completion of the movement of the switch for removing the obstruction, and a circuit closed at the extreme limit of movement of the moving part exclusive of the block relay control for holding the switch-throwing mechanism against movement of the switch.
